FIGURE TOY

Evelyn Gustafsson, New York, N. Y.

Application October 6, 1936, Serial No. 104,170.

12 Claims. (Cl. 46—156)

The present invention relates to toys, and more particularly, to toy figures.

One object of the present invention is to produce a wide variety of toy figures from the same structural elements.

Another object of the invention is to provide a toy figure of novel construction and appearance.

A further object of the invention is to provide a toy figure of simple construction and capable of being readily produced from preformed tubular elements and capable of being readily assembled together.

More specifically, the present invention resides in the production of toy figures from tubular members, such as drinking straws of the type used at soda fountains, and more particularly, drinking straws made of transparent sheet cellulosic material known as "Cellophane", it being understood that by the term "Cellophane", I mean not only regenerated cellulose, but also other sheet cellulosic material such as that derived from cellulose ethers and from cellulose esters, some of which are sold under the trade-names of "Protectoid" and "Kodapak". However, for convenience in reference, the term "Cellophane" will hereinafter be utilized to designate sheet cellulosic material of the general class referred to, and which is characterized by its resiliency, hardness and usually by its transparency, although materials of this character may be opaque. The "Cellophane" tubes utilized for the purpose of my invention may be made of ordinary "Cellophane" or of waterproof "Cellophane". Also as is well known "Cellophane" is produced in various colors in addition to the well known normal color thereof. The tubes are preferably of the type which are produced by spirally winding strips of "Cellophane" and by adhesively securing said spirally wound strips in tube forming relation.

In producing the figure toys, in accordance with the present invention, a plurality of the "Cellophane" tubes are assembled in simulation of the figure and preferably, the tubes are bent so that the several portions of the figure are in integral relation, parts of the same tubes being utilized for simulating the various parts of the figure. For example in producing a toy figure simulating a horse or pony, a group of "Cellophane" tubes are arranged to simulate the body portion of the animal, and integral portions of said tubes are bent to simulate the legs, head, ears and tail of the animal, although it is within the scope of the present invention to constitute

one or more parts of the figure from separate tubes. The figure toys may be produced entirely from the "Cellophane" tubes, suitable means being utilized for holding the tubes together in figure-simulating position, but I may also utilize other elements to assist in obtaining different effects. Thus, for example, I may utilize stiffening wires positioned within the tubes to stiffen the figure or different parts thereof. For holding the tubes in position, numerous means may be employed such as elastic or inelastic cords, tapes, etc., or I may adhesively secure the tubes or portions thereof together by the use of heat when the material of the tube is rendered adhesive in response to heat, or by a solvent for the material of the tubes, or by other adhesive substances.

The present invention, and the above objects and features thereof, will be more fully understood from the following description considered with reference to the accompanying drawing forming a part of the present specification.

In the drawing:

Fig. 1 is a perspective view of a figure toy embodying the present invention;

Fig. 2 is a sectional view on the line 2—2 of Fig. 1;

Fig. 3 is a sectional view on the line 3—3 of Fig. 1;

Fig. 4 is a perspective view of another toy figure which may be made in accordance with the present invention;

Fig. 5 is a sectional view on the line 5—5 of Fig. 4;

Fig. 6 is an enlarged sectional view on the line 6—6 of Fig. 4;

Fig. 7 is a more or less diagrammatic view illustrating the arrangement and formation of the tubes in producing a toy figure, for example, that shown in Fig. 1.

Referring to the drawing in detail, the toy figure 10 shown in Fig. 1, and the toy figure 12, shown in Fig. 4, are illustrative of only two of a large number of different toy figures which may be produced in accordance with the present invention. Thus, for example, Fig. 1 represents a fanciful simulation of a mule, while Fig. 4 illustrates a person in a skiing costume. Numerous other figures may be produced in accordance with the teachings of the present disclosure.

Referring, first, to Figs. 1 to 3, and 7, in producing the toy figure 10, a plurality of "Cellophane" tubes 14 are grouped together in substantially parallel relation in which the tubes extend longitudinally and are arranged to form

a curved outline to simulate the body portion 16 of the figure. Some of the tubes are reflexed downwardly at both ends to form the front and hind legs 18 and 20 of the figure, while other tubes are bent upwardly and then downwardly at the front of the figure to form the neck 22 and the head 24. The rear end of said last mentioned tubes are reflexed and are preferably braided together to simulate a braided tail 26. Additional tubes 28 are grouped at the front of the figure together with the portions forming the front legs 18, the neck 22 and the head 24, and have folded portions 30 to simulate the ears of the figure.

15 The tubes are held together in the desired relation by any suitable means here shown as rubber or other elastic bands 32. As the tubes are resilient they may be compressed more or less in different portions thereof or flattened to obtain 20 the desired appearance of the figure in the different parts thereof. Thus, for example, in the rear part of the body of the figure, the tubes are more compressed than the front part of the body portion of the figure so that the rear part of the figure is of smaller diameter than the front of the body portion. This may be readily accomplished by using elastic cords of different sizes or inelastic cords and tightening them about the different parts of the figure as may be necessary 25 to obtain the desired appearance. Instead of a plurality of cords, I may use a continuous tape or cord wound about the figure or parts thereof. The different effects obtainable by utilizing the "Cellophane" tubes is also indicated by the flat 30 portions of the tubes in the tail and ear portions of the figure, the flattened tubes in the tail portion being braided together to simulate a braided tail. The elastic band 32 in addition to its function of fastening means for holding the tube 35 portions together also simulates the fastening ribbon frequently used on a braided tail of a live animal. By flattening the tubes in the ear portions, the latter more closely simulate the natural ears of the live animal. In the construction 40 just described, the figure is supported in upright position without any stiffening means other than that inherent in the tube portions which form the front and hind legs of the figure.

In Fig. 4 the invention is illustrated as applied 50 to a simulated human figure, represented as a person in skiing costume and wearing skis. As here shown, the body portion 40, the head 42, the arms 44 and the legs 46 are formed from "Cellophane" tubes arranged in groups and held in the 55 specified relation by elastic bands 48 or by some other suitable means. The skis 50 are also represented by "Cellophane" tubes disposed in juxtaposition to the feet of the figure. Preferably, the figure is reinforced by metal wires 52 which 60 extend longitudinally of the figure and are concealed by the "Cellophane" tubes. Said wires have lower horizontal portions 54 which project forwardly of the figure and are reflexed in spaced 65 relation to outline roughly the formation of skis. This appearance is improved, as here shown, by positioning the wires within the tubes 50 so that the "said" wires are substantially concealed thereby.

70 Thus, it is seen that the constructions herein illustrated are well adapted to accomplish the several objects of the present invention. It will be understood that a wide variety of novel effects may be obtained by producing figures of different types in simulation of various natural figures. 75 As "Cellophane" tubes are available in a plurality

of different colors, it is apparent that by utilizing in a single figure tubes of different colors various pleasing and readily variable ornamental effects may be obtained. Thus, for example, tubes of one color may be arranged to simulate the body 5 portion of the skiing figure illustrated in Fig. 4, while the toque 56, worn by the figure, may be made of tubes or of "Cellophane" material of different color. Also, the elastic bands utilized for holding the tubes in assembled relation may be 10 of a color which contrasts with the color of the tubes and thereby further add to the different color combinations which can be obtained in accordance with the present invention. It will be understood that in lieu of the elastic bands or 15 other fastening elements, the tubes may be held in proper position by means of any suitable adhesive or by subjecting the material of the tubes in their assembled relation to the action of heat or of a solvent, or of both heat and solvent, to 20 render said tubes adhesive. Numerous other variations in the construction and arrangement of parts of the embodiments herein illustrated may be made, and other embodiments of the invention may be readily produced following the 25 teachings of this specification. Therefore, I do not wish to be limited precisely to the constructions herein shown or described, except as may be required by the appended claims considered 30 with reference to the prior art.

Having thus described my invention, what I claim and desire to secure by Letters Patent is:

1. A toy figure comprising a plurality of "Cellophane" tubes arranged in simulation of the body, head and limbs of the figure, and means for holding said tubes in said arrangement.

2. A toy figure comprising a plurality of "Cellophane" tubes arranged in simulation of the figure, and means for holding said tubes in said arrangement.

3. A toy figure comprising a plurality of "Cellophane" tubes arranged in simulation of the figure, means for holding said tubes in said arrangement, and means associated with said tubes for stiffening a part of the figure.

4. A toy figure comprising a plurality of "Cellophane" tubes arranged in simulation of the figure, means for holding said tubes in said arrangement, and wire elements associated with some of said tubes for stiffening a part of the figure.

5. A toy figure comprising a plurality of "Cellophane" tubes arranged in simulation of the figure, means for holding said tubes in said arrangement, and a wire element disposed within some of said tubes for stiffening a part of the figure.

6. A toy figure comprising a plurality of slender elongated tubular elements composed of cellulosic sheet material, said elements having portions extending longitudinally of the figure and defining the body thereof and reflexed portions arranged in simulation of the limbs of the figure, and means for holding said elements together in figure simulating relation.

7. A toy figure comprising a plurality of slender elongated tubular elements composed of cellulosic sheet material, said elements having portions extending longitudinally of the figure and defining the body thereof and reflexed portions arranged in simulation of the limbs of the figure, and means for holding said elements together in figure simulating relation and means associated with said tubes for stiffening a part of the figure.

8. A toy figure comprising a plurality of slender

elongated tubular elements composed of cellulosic sheet material, said elements having portions extending longitudinally of the figure and defining the body thereof and reflexed portions arranged in simulation of the limbs of the figure, means for holding said elements together in figure simulating relation, and wire elements associated with some of said tubes for stiffening a part of the figure.

9. A toy figure comprising a plurality of slender elongated tubular elements composed of transparent and colored cellulosic sheet material, said elements having portions extending longitudinally of the figure and defining the body thereof and reflexed portions arranged in simulation of the limbs of the figure, and means for holding said elements together in figure simulating relation.

10. A toy figure comprising a plurality of slender elongated tubular elements composed of

transparent cellulosic sheet material, said elements having portions extending longitudinally of the figure and defining the body thereof and reflexed portions arranged in simulation of the limbs of the figure, and means for holding said elements together in figure simulating relation.

11. A toy comprising a plurality of "Cellophane" tubes arranged in simulation of the body, head and limbs of an animal figure, some of said tubes having reflexed portions extending from the body portion of the figure and forming the limbs thereof.

12. A toy comprising a plurality of "Cellophane" tubes arranged in simulation of the body, head and limbs of an animal figure, some of said tubes having reflexed portions extending from the body portion of the figure and forming the limbs thereof, and means associated with said tubes for stiffening a part of the figure.
